ILLUMINATED AQUARIUM LAMP

Filed Aug. 29, 1925

Inventor
Charles Emma

By *John A. Dinenen*
his Attorney

UNITED STATES PATENT OFFICE.

CHARLES EMMA, OF PHILADELPHIA, PENNSYLVANIA.

ILLUMINATED AQUARIUM LAMP.

Application filed August 29, 1925. Serial No. 53,286.

This invention relates to improvements in decorative lamps, and has for an object to provide a lamp in which the light is controlled and the beams restricted to pass 5 through a novel diffusing medium.

A further object is to provide a lamp of this character in which the diffusing medium may be utilized to produce various and novel decorative effects as will be more fully 10 explained hereafter.

A further object is to construct such a lamp that the parts may be easily accessible, and the diffusing medium may be conveniently and readily changed from one arrangement to another. 15

A further object is to construct a lamp in which the diffusing medium may be fully protected from injury and at the same time lend itself to appropriate decoration suitable to the diffusing medium employed. 20

With these and other objects in view as may become apparent from the following disclosure, the invention consists in the novel combination of elements, construction 25 and arrangement of parts, operation and specific features to be hereinafter enlarged upon and recited in the subjoined claims, the invention being illustrated in the accompanying drawings wherein:

30 Figure 1 is an elevation of my device;
Figure 2 is a horizontal section; and
Figure 3 is a vertical section.

Referring to the drawings a base A provided with felt or rubber pads 5 supports a 35 body portion B of suitable decorative contour having an enlarged central cavity 6 and supporting a decorative casing C preferably made in sections and hinged at 7 for opening to give access to the interior. An 40 appropriately decorated cap D rests on the decorative casing and serves to support a tubular standard 8 for a light cluster E which may or may not be used at the time the main illuminating device is in operation.

45 A lamp F mounted in the central cavity of the base projects through an opening 9 in a frustro conical mirrored reflector 10 mounted to throw the beams from the light upwardly within the casing.

50 A glass globe G of suitable cross section is mounted within the casing on felt or rubber pads 11 so that it is spaced from the base, and may be filled with water and serve as an

aquarium or for a receptacle within which a fountain (not shown) may be made to play 55 and direct its waters down the interior walls.

A vaned and multicolored shield H may be mounted on the tip of the lamp F so that the heat from the lamp revolving the vane the light will be shown of different color 60 passing upward to the aquarium.

The base B may be suitably apertured as at 12 for the accommodation of the light circuit wires 14 from which a lead 15 may carry the current upwardly within the casing and through the standard 8 to the light cluster. A suitable switch 16 may be supplied and may be conveniently mounted in the base, as shown.

As is obvious rays from the lamp will be 70 directed upwardly so that the water in the globe will be lighted throughout illuminating objects, as fishes, swimming in the water, and the light will be diffused and send a glow through the decorated casing. 75

While a design of trees and shrubbery is conventionally shown as a filigree or cutout decoration for the casing, it will be appreciated that any other suitable design may be used, the parts thereof serving to protect 80 the glass globe from casual injury.

While in the foregoing I have described specific embodiments, and have mentioned only certain possible modifications, it will be appreciated that in practice I do not 85 limit myself to such specific details as herein set forth, but may resort to any practical modifications falling within the scope of the claim.

What I claim and desire to secure by Letters Patent of the United States is:

A lamp comprising a base, a light within the base, a diffusing medium spaced from the base and comprising a container having a liquid filler, a reflector to direct rays upwardly from the light through the diffusing medium, and a protective casing supported on the base to surround the diffusing medium and spaced therefrom, parts being removed to leave decorative designs as a shade for the lamp, and a multi-colored shield revolvably mounted between the light and the diffusing medium. 95 100

In testimony whereof I affix my signature.

CHARLES EMMA.
